METHOD AND APPARATUS FOR INSIDE BLOWOUT PREVENTER DRILLING TOOL

CROSS-REFERENCES TO RELATED APPLICATIONS

The method and apparatus set forth in the present application is related to the disclosure of my application now entitled "Inside Blowout Preventer Drilling Tool," filed Nov. 24, 1971 and assigned Ser. No. 201,878, now U.S. Pat. No. 3,783,942, and my application Ser. No. 212,260, filed Dec. 27, 1971, and entitled "Drilling Tool."

BACKGROUND OF THE INVENTION

This invention relates to the field of a method and apparatus for a drilling tool for controlling blowout flow through the bore of a tubing.

Prior Art inside blowout preventer drilling tools, such as disclosed in my applications identified hereinabove, have been of the type having a valve element which was operated to normally be urged to move to and remain in the closed position and which was operably moved to the open position by a valve operator means in response to certain conditions or operations, insuring flow in the desired downwardly direction. When such prior art valves operated to shut-in a blowout flow, it was necessary to circulate a heavier drilling fluid in the well to bring the well pressure back under control. In addition, the prior art valves required a greater pressure, on the order of several hundred P.S.I. in the bore to open and hold the valve in the open position. Of course with the valve closed, the well pressure below the tool effecting the blowout could not be sensed for determining the weight or hydrostatic pressure of drilling fluid required for controlling the well and the driller was forced to either guess or estimate what increase in density of the drilling fluid was required to bring the well under control. The expense of both the lost drilling time while circulating to bring the well under control and of the weight additives for increasing the density of the drilling fluid had limited the use and acceptance of prior art tools.

SUMMARY OF THE INVENTION

This invention relates to the field of a new and improved method and apparatus for an inside blowout preventer drilling tool.

In the present invention, an inside blowout preventer drilling tool is arranged to operate in response to substantially equal drilling pressures for enabling drilling operations and for closing the flow passage of a drilling string when well conditions effect uncontrolled flow. With the present invention, well conditions below the drilling tool may be sensed or measured for determining the requirements for bringing the well back under control.

An object of the present invention is to provide new and improved inside blowout preventer drilling tool apparatus.

A further object of the present invention is to provide a new and improved method for operating an inside blowout preventer drilling tool.

BRIEF DESCRIPTION OF THE DRAWINGS

FIG. 1 is a partial side view, in section, of the apparatus of the present invention in the open position;

FIG. 2 is a partial side view, in section, with the apparatus of the present invention operated closed;

FIG. 3 is a partial side view, in section, of another form of the apparatus of the present invention operated open;

FIG. 4 is a partial side view, in section, with the apparatus of FIG. 3 operated closed; and

FIG. 5 is a side view, in section, of a well with the apparatus of the present invention operably installed in the drill string.

DESCRIPTION OF THE PREFERRED EMBODIMENT

As illustrated in FIG. 5, the inside blowout preventer 15 drilling tool of the present invention, generally designated T in the FIGS., is adapted for mounting in a well conduit or drill string S above the drill bit B to control undesired upwardly or uncontrolled blowout flow which may occur during drilling operations when a high 20 pressure formation F is penetrated by the drill bit B. A rotary table means R at the surface or ground level G co-acts with a kelly K for imparting rotational movement to the drill string S and the drill bit B for providing the desired rotary cutting action while a hoisting means 25 (not illustrated) controls the vertical, longitudinal movement of the drill string S and the drill bit B in the well known manner. During drilling operations, drilling fluid is circulated by a pump means P on the surface G 30 through a swivel or other suitable connection C into the bore of the kelly K and the bore passage X of the drill string S to the drill bit B where it is jetted into the bore-hole H through the nozzles N. The drilling fluid then circulates back to the surface or ground level G in the 35 annular area between the drill string S and the walls of the borehole H to the pump supply pit or tank W where it is available for recirculation by the pump means P. Normally, the weight of the column of drilling fluid in the bore hole H provides a sufficient hydrostatic pressure to control the fluid pressure found in the formation F. When the fluid pressure in the formation F exceeds the hydrostatic head or well conditions are out of 40 control for any reason, the inside blowout preventer drilling tool T of the present invention operates to control the flow in the bore X.

In the embodiment of the drilling tool T illustrated in FIGS. 3 and 4, the tool T includes a tubular member frame 10 mounted with and forming a portion of the drill string S at a desired location in the string S. Threads 11 and 12 formed on the frame 10 provide the 50 means for connecting the upper and lower ends, respectively, of the frame 10 in the drill string S. A full opening flow passageway 13 is provided through the frame 10 to enable circulation of drilling fluid to the drill bit. Formed through the frame 10 is one or more 55 radially extending ports 14 for communicating the well pressure in the bore hole H adjacent exterior surface 15 of the frame 10 to the flow passage 13.

The drilling tool T further includes a closing means, 60 generally designated 20, movable to and from an open position for enabling desired flow through the drill string S and a closed position for blocking undesired upwardly flow through the drill string S and an operator means, generally designated 30, for effecting desired operational movement of the closure means 20.

The closure means 20 includes a substantially spherical or ball shaped member 21 having a full bore opening or passageway 22 extending therethrough and seal

means or seats 23 and 24, located above and below the ball 21, respectively, engaging a spherical surface 25 for effecting a fluid tight seal with the ball 21 to block leakage of fluid therebetween. The ball 21 rotates between the open position in which the opening 22 is substantially aligned with the bore flow passage 13 and a closed position in which the opening 22 is located substantially transverse to the bore 13 for blocking flow with the ball 21. The full bore opening 22 provides a cross-sectional flow area therethrough substantially equal to the cross-sectional flow area of the bore X of the drill string S to reduce or minimize pressure loss during circulation of the drilling fluid.

The operator means 30 includes a movable operator sleeve member 31 located adjacent and operably connected with the ball 21 to effect the desired pivoting or rotational movement thereof. The ball 21 includes spaced parallel circular flat surfaces 26 having radially extending recesses or grooves 27 formed therein. Pins Y threadedly secured to the sleeve 31 at aligned eccentrically located positions extend within the grooves 27 to effect rotation of the ball 21 when there is relative longitudinal movement between the ball 21 and the operator sleeve 31. In the present embodiment, the ball 21 only rotates when the sleeve 31 moves longitudinally to and from a first or down position (FIG. 3) for rotating the ball to the opening position and a second or upper position (FIG. 4) for rotating the ball to the closed position. If further explanation or description of the manner of rotating the ball 21 is desired, reference may be had to my co-pending applications identified hereinabove, or to U.S. Pat. Nos. 3,126,908; 2,894,715; 3,667,505; Re. 25,471 and 3,035,808.

The operator means 30 includes a piston means 32 formed by the sleeve 31 for effecting movement of the sleeve 31 to move ball 21 in response to the various pressure urgings on the piston means 32. The sleeve 31 is slidably sealed to the housing 10 by O-rings 34a and 34b carried by the sleeve 31 resulting in an upper annular shoulder 33 of the sleeve 31 forming a first or upwardly facing annular surface for urging movement of the sleeve 31 to the lower position in response to the pressure in a first expandable chamber 35 formed by the sleeve 31 in the housing 10 urging on the shoulder 33. The annular expandable chamber 35 communicates with the flow passage 13 through a plurality of ports 36 formed in the housing 10 for exposing the shoulder 33 to the fluid pressure present in the flow passage 13 and the bore X of the drill string S.

The sleeve 31 is slidably sealed to the housing 10 by O-rings 37 and 38 for forming a second or lower expandable chamber 39 with a lower annular shoulder 40 of the sleeve 31 forming a second or downwardly facing annular surface for urging movement of the sleeve 31 to the upper position in response to the fluid pressure in the chamber 39 urging on the shoulder 40. The lower annular expandable chamber 39 communicates through the ports 14 with the area adjacent the exterior of the tool T. An O-ring 41 mounted with a lower removable sleeve 42 of the housing 10 blocks leakage of fluid between the expandable chamber 39 and the flow passage 13 of the housing 10.

The removable sleeve 42 includes a smaller outer diameter upper portion 43 above the O-ring 38 forming an upwardly facing annular shoulder 44 which engages a downwardly facing annular shoulder 31a (FIG. 3) on the sleeve 31 for providing a lower movement stop for

the sleeve 31. The different outside diameter portions of the sleeve 42 cooperate with the movable sleeve 31 to form an annular expandable chamber 45 above the shoulder 44, which communicates with the flow passage 14 through a plurality of circumferentially spaced ports 46 formed through the upper portion 43 of the sleeve 42 for urging on the pressure responsive effective surface of the sleeve 31 formed by the shoulder 31a to urge upward movement of the sleeve 31 to the upper position in response to the pressure in the flow passage 13 in the bore X of the drill string S.

The operator means 30 further includes a spring 47 or means for urging the operation or movement of the sleeve 31 to the lower position which is located in the upper expandable chamber 35. The spring 47 is mounted with the housing 10 by engagement with the shoulder 48 formed by an upper removable sleeve 49 forming a portion of the housing 10 and engages the shoulder 33 of the sleeve 31 for urging movement of the sleeve 31 to the lower position.

Of the four forces urging operating movement of the sleeve 31, two are urging downward movement and two are urging upward movement. The spring 37 and the pressure in the chamber 35 urge downwardly to open the ball 21 while pressure in the chambers 39 and 45 urge to close the ball 21. However, fluid pressure communicated into the chambers 45 and 35 is the same when the ball 21 is rotated open and therefore these urgings would be offsetting or mutually cancelling to a predetermined extent. The pressure in the chamber 35 urging on the greater pressure responsive area 33 would still provide a net downwardly urging on the sleeve 31 predetermined by the difference in the relative size of the pressure responsive effective surface areas 33, 31a and 40. In the embodiment illustrated in FIGS. 4 and 5; the pressure responsive area 33 is equal to the pressure responsive areas of the shoulders 14 and 31a. By varying the relative size of the effective areas 14 and 31a, the operating parameters of the valve may be predetermined varied or controlled.

For example, when the ball 21 is rotated open the pressure in the well conduit urging a portion of the surface 33 not offset by the surface 31a together with the spring 37 will urge the sleeve 31 to remain in the lower position. To move the sleeve 31 to close the ball 21 the pressure exteriorly of the tool T and in the chamber 42 must provide an urging on the shoulder 40 of the sleeve 31 exceeding the combined urging of the pressure in the drill string urging downwardly on the non-offset portion of the surface 33 and the urging of the spring 47. Of course, the shoulder 40 may be provided with a predetermined larger effective surface area than that of shoulder 33 in order that the valve will close when the pressures are substantially equal. With the ball 21 rotated closed (FIG. 4) the pressure exteriorly of the tool effecting closure of the ball 21 will also be communicated through the drill bit nozzles N into the flow passage 13 below the ball 21 and into the chamber 45. The well pressure effecting closure will then be present in both expandable chambers 39 and 45 for maintaining the sleeve 31 in the upper position and the ball 21 rotated closed. To move the sleeve 31 downwardly to open the ball 21, the pressure in the bore X of the drill string S above the ball 21 is increased by the use of pump means P or the like to approach the pressure in the chambers 45 and 39 urging the ball closed. When the increased pressure in the flow passage 13 above the

ball 21 approaches the pressure in the chambers 39 and 45 to bring the fluid pressure urging on the sleeve 31 within a predetermined offsetting range, the spring 37 will move the sleeve 31 to the lower position and open the ball 21. Of course, selecting a spring 37 with a desired spring constant will control or predetermine the range or value to which the pressure in the chamber 35 must approach the pressure in the chambers 45 and 39 to open the valve. With this arrangement, the valve is preferably set to operate closed in response to the urging of a pressure differential range approaching 60 PSI on the sleeve 31.

When the ball 21 is rotated open, the pressure in the flow passage 13 above the ball 21 will be increased by equalization in which increased pressure will be communicated into the chamber 35 for equalizing or offsetting the pressure urgings on the sleeve 31, which assures that the sleeve 31 will move to the lower position and eliminates the possibility of potentially damaging flow throttling by the ball 21.

In summary, increased pressure from exteriorly of the tool T, in the chamber 39, will effect closing rotation of the ball 21 while increasing the pressure in the bore X of the drill string S above the ball 21 to approach within a selected or predetermined range of the pressure exteriorly of the tool T will rotate the ball 21 open.

A second embodiment of the well tool T of the present invention having a tubular assembly 100 dimensioned to be introduced or inserted in the flow passage 101 of a drill string pipe or sub 102 for controlling flow of fluid to the drill string S is illustrated in FIGS. 1 & 2. The sub 102 is provided at its upper end with threads 103 and at its lower end with threads 104 for connecting the sub 102 in the drill string S for forming a portion thereof at a desired location. The flow passage 101 is formed adjacent the threads 103 to provide a downwardly facing annular shoulder surface 104 which engages the tubular assembly 100 for blocking upward movement of the tubular assembly 100 from the flow passage 101 of the sub 102. The portion of the drill string S below the sub 102 secured to the thread 104 blocks downward movement of the tubular assembly 100 from the flow passage 101 of the sub 102.

The tubular assembly 100 includes a longitudinally extending passageway or opening 106 extending therethrough for enabling communication with the bore X of the drill string S through the opening 106. The opening 106 is provided with a cross-sectional flow area substantially equal to the cross-sectional flow area of the bore X of the drill string S for forming a full bore opening tool T. The tubular assembly 100 carries a lower seal ring means 107 for effecting a seal between the tubular assembly 100 and the sub 102 for blocking the passage of fluid therebetween and directing the flow of the fluid in the bore X of the drill string S through the bore 106 of the tubular assembly 110. The seal means 107 is also arranged for enabling fluid pressure introduced between the sub 102 and the tubular assembly 100 to force or urge the tubular assembly 100 to move downwardly from within the sub 102 when the engagement at thread 104 is disconnected.

The tubular assembly 100 includes an upper fixed sleeve 108 having an upper annular shoulder 108a which partially engages the shoulder 104 of the sub 102 for holding the tubular assembly 100 against upward movement in the sub 102. Concentrically positioned

within the longitudinally extending opening through the sleeve 108 and secured therein is the sleeve 109 having an upwardly facing shoulder 109a engaging a downwardly facing shoulder 108b for blocking upwardly movement of the sleeve 109 relative to the sleeve 108. A restraining device or snap ring 110 partially fits in an annular groove 109b in the sleeve 109 and engages the shoulder 108a to block downward movement of the sleeve 109 relative to the sleeve 108. 10 The sleeve 108 carries a seal ring 111 for effecting an annular seal with the sub 102 to block leakage or passage of fluid between the sub 102 and the tubular assembly 100.

The sleeve 108 extends downwardly from the seal 15 111 to mount an annular seal ring 112 at the lower end of the sleeve 108. The inside surface 108c forming the opening through the sleeve 108 includes a downwardly facing annular shoulder 108d engaging or resting on a plurality of circumferentially spaced radially outwardly 20 extending lugs or projections 113a formed on a sleeve 113 for blocking upward movement of the sleeve 113 relative to the sleeve 108. The sleeve 113 forms a portion of the full bore opening for flow passage 106 through the tubular assembly 100 and concentrically 25 mounts at its lower end a seat ring 123 engaging a bore closure means or ball 121 for blocking flow through the opening 106. Concentrically mounted at the upper end of the sleeve 113 by threads 113b is a resilient tubular 30 diaphragm 150 which is secured at its upper end to threads 109c of the sleeve 109 to form a portion of the flow passage 106 through the tool T. The diaphragm 150 is radially flexible for purposes to be set forth in greater detail hereinafter.

35 Located below the ball 121, the illustrated tubular assembly 100 includes the sleeve 114 concentrically mounting a lower seat ring 124 in sealing engagement with the ball 121 and forming a portion of the opening 106 through the tubular assembly 100. A securing ring 40 115 is secured to the lower outer threaded surface 114a of the sleeve 114 for providing a lower limit stop to a relatively movable sleeve 116 by engagement of a downwardly facing annular shoulder 116a with an upwardly facing annular shoulder 115a of the securing ring 115. Concentrically mounted exteriorly of the sleeve 114 above the securing ring 115 is a seal carrying ring 117 for mounting the seal ring 107 and which also mounts an O-ring 118 for blocking leakage of fluid between the seal mounting ring 117 and the sleeve 114. 50 The seal carrying ring 117 forms an upwardly facing annular shoulder 117a which engages a downwardly facing annular shoulder 114b formed on an outer surface 114c of the sleeve 114 to block or limit upward movement of the seal carrying ring 117 relative to the sleeve 114. Positioned between an upwardly facing annular surface 116b and a downwardly facing shoulder 55 117b of the ring 117 is a biasing or spring means 119 to provide a length adjustor or compensator for the tubular assembly 100 for holding the tubular assembly 100 in engagement with the shoulder 105 of the sub 102 while enabling fluid tight engagement of threads 104 with the drill string S. The sleeve 116 engages the drill string S with the lower annular shoulder 116c to block downward movement of the tubular assembly 100 from the flow passageway 101 of the sub 102 and the limited range of longitudinal movement of the sleeve 116 assures the tubular assembly 100 is held in 60 65

engagement with the annular shoulder 105 despite variations in makeup of the drill string S at threads 104.

The embodiment of the tool T, illustrated in FIGS. 1 and 2, also includes a bore closure means 120 and an operator means 130 for effecting operation of the bore closure means 120.

The bore closure means 120 includes the ball 121 and the seats 123 and 124 which engage an outer spherical surface 121a for effecting annular fluid type seals with the ball 121. The ball includes a flow passage 121b, formed therethrough which preferably is of the same cross-sectional flow area as that of the opening 106 to the tubular assembly 100 in order that the well tool T provides a full bore opening therethrough substantially equal to the cross-sectional flow area of the bore X of the drill string S to minimize pressure loss of the drilling fluid flowing through the tubular assembly 100. The ball 121 is rotatably mounted with the tubular assembly 100 to align the opening 121b with the passage 106 for enabling flow through the opening 106 and which is rotatable to a closed position with the opening 121b substantially transverse to the opening 106 for blocking flow of fluid through the opening 106 and the bore X of the drill string S.

The operator means 130 includes a longitudinally movable sleeve operator member 131 concentrically mounted exteriorly of the ball 121 and which is movable to and from a first or lower position effecting opening rotation of the ball 21 (FIG. 1) and a second or upper position affecting closing rotation of the ball 121 (FIG. 2). The operator sleeve 131 carries inwardly projecting lugs or pivot pins 132 which are eccentrically secured to the sleeve 132 for longitudinal movement and which extend within radial recesses 121c formed in the flats 121d for effecting the desired rotation of the ball 121.

The operator means 130 includes a piston means 133 preferably formed by an upper operator piston sleeve 134 and a lower piston operator sleeve 135 secured together by threaded engagement at 136. An upwardly facing annular shoulder 135a of the lower sleeve 135 engages the bottom of the operator sleeve 131 while a downwardly facing annular shoulder 134a engages the top of the operator sleeve 131 for securing the three operator sleeves to form an integral operator unit or member moving longitudinally for rotating the ball 121 in the desired manner.

The lower piston sleeve 135 carries the seal 137 for effecting a sliding seal with the sub 102 for blocking leakage of fluid therebetween. Mounted on the exterior surface 114d of the sleeve 114 is a seal 138 for effecting a sliding seal between the sleeve 135 and the sleeve 114. The annular area of the sleeve 135 between the seals 137 and 138 form a downwardly facing pressure responsive surface which will be referred to and identified hereinafter as the lower annular shoulder 135b.

The tubular assembly 100, the operator sleeve 135 and the sub 102 form a second annular expandable chamber 140 defined by seal rings 137 and 138 at the upper end and seal rings 107 and O-ring 118 at the lower end. Fluid pressure in the chamber 140 urges on the annular pressure responsive effective surface area 135b of the sleeve 135 to urge the operator sleeves 132, 133 and 135 to the upper or second position for rotating the ball 121 closed. Fluid pressure in the chamber 140 also urges on the upwardly facing annular shoulder 117a of the seal ring 117 for urging movement of the

tubular assembly 100 from the flow passage 101 of the sub 102 when the drill string is disconnected at thread 104. Extending through the sub 102 is one or more flow ports 102a for communicating the chamber 140 with the area adjacent an exterior surface 102b of the sub 102. The flow port or opening 102a may be provided with threads 102b for connection with a supply of fluid pressure to force the tubular assembly 100 from the flow passage 101 when the drill string S was disconnected at threads 104. To accomplish this removal it is necessary that the pressure responsive effective surface area 117a be larger than the pressure responsive effective surface area between the seals 137 and 138 to provide a net downwardly urging on the tubular assembly 100.

As best illustrated in FIG. 1, the movable upper operator sleeve 134 carries seal rings 141 and 142 to effect sliding annular seals with the sub 102 and the sleeve 113 of the tubular assembly 100, respectively, to block leakage of fluid by the sleeve 134. The sleeves 141 and 142, along with the diaphragm 150, define a first or upper enclosed annular chamber 143 in communication through the openings between the lugs 113a. Fluid pressure in the chamber 143 will urge on the upwardly facing pressure responsive annular shoulder surface 134b of the sleeve 134 for moving the operator sleeves 132, 134 and 135 to the first or lower position for rotating the ball 121 to the open position.

The chamber 143 is filled with a pressure transmitting fluid, such as hydraulic oil or grease, in order that fluid pressure in the bore of the drill string S and the flow passage 106 above the ball 121 urging on an inner surface 150a of the diaphragm will be transmitted to the pressure responsive surface 134b for urging thereon. The pressure in the flow passage 106 will move or urge the diaphragm 150 to flex radially outwardly as the operator sleeve 134 moves downwardly to continually transmit the pressure in the flow passage 106 with an outer surface 150b of the diaphragm urging on the pressure transmitting fluid. With this arrangement solid particles in the drilling fluid are excluded from the pressure responsive chamber 143 and will not interfere with, bind, hinder, or block movement of the operator sleeves 132, 134 and 135.

The upwardly facing pressure responsive surface 134b is also formed to effect secondary seals with an inner annular seal 144 carried by the sleeve 113 and the outer annular seal 112 carried by the sleeve 108 when the sleeve 134 is in the upper position. The secondary seal so effected by seal rings 144 and 112 reduce the effective pressure responsive surface area 134b of the sleeve 134 when the ball 121 is in the closed position. As the sleeve 134 commences to move downwardly for rotating the ball 121 open and away from the seats 112 and 144, the size of the pressure responsive surface area 134b is increased for assuring positive movement of the sleeve 134 to the lower position. This arrangement avoid equalizing of the pressure urging on the operator 132 between the upper and lower positions resulting in the ball 121 rotated only partially open. When the ball 121 is partially open, the pressure drop across the flow passage 106 is increased and damage to the sealing surfaces is probable.

The ratios of the pressure responsive effective surface area of the surface 134b when sealed by the O-rings 112 and 144 and when spaced from those secondary seals to the pressure responsive effective surface

area 135b will predetermine or control the pressure value or differential between the chambers 143 and 140 for effecting operation of the ball 121. With this illustrated embodiment, a pressure in the chamber 140 approximately 25 psi higher than the pressure in the chamber 143 will effect closing rotation of the ball 121 from the open position. The secondary sealing arrangement preferably requires an increased pressure exceeding the well pressure to open the ball 121. Both well tool embodiments disclosed herein are arranged to be unusually sensitive to the pressure differential urgings thereon and are operable in response to substantially equal or slightly different pressures when compared to the prior art inside blowout preventer well tools.

The operator means 130 includes releasable latching or locking means for sufficiently delaying movement of the operator sleeve from the lower position to prevent or block momentary pressure fluctuations for effecting closing rotation of the ball 121. Extending downwardly from the shoulder 135b of the lower operator sleeve 135 is a plurality of resiliently deformable circumferentially spaced arms or projections having radially inwardly extending lugs 161 formed on the lower end. The lugs 161 are aligned with an annular recess 114e formed in the outer surface 114c of the sleeve 114 for providing a downwardly facing locking shoulder 114f for engaging an upwardly facing surface 161a of the lugs 161 for holding the ball 121 in the open position. The arms 160 will flex radially outwardly to enable the lugs 161 to be wedged from beneath the surface 114f by a greater pressure in the chamber 140 and in the chamber 143 for a small, but effective, length of time to flex the fingers 160 outwardly. The deformation of the fingers 160 is controlled by an adjustment ring 162 concentrically mounted exteriorly of the fingers 160 by moving the ring 162 longitudinally towards the lugs 161. The delay in closing may be increased by increasing the amount of force required to disengage the lugs 161 from the recess 114e. The adjustment ring 162 is provided with a set screw 163 to hold the adjustment ring 162 in the desired position along the arms 160. Preferably the adjustment ring 162 is set to insure that the ball 120 is not rotated closed as the drill string is lowered in the bore hole H towards the formation F. This enables the bore X of the drill string S to fill with drilling fluid in the bore hole H through the nozzles N of the drill bit B and avoid the need to connect the drill string S with the pump means P for filling the drill string S above the tool T with drilling fluid to prevent collapse of the drilling string S. This feature is accomplished in the first described embodiment by proper selection of the spring 47 for maintaining the ball 21 rotated open.

OPERATION AND USE OF THE PRESENT INVENTION

In the operation and use of the first described embodiment (FIGS. 3 & 4) of the well tool T of the present invention, the tubular frame 10 is connected in the drill string S in the desired location. Pressure is then increased in the bore X of the drill string S above the ball 22 for urging on the surface 33 to effect opening rotation of the ball 22. Thereafter, as additional sections of drilling string are added and the well tool T lowered deeper in the bore hole H, the urging of the spring 47 will maintain the ball 21 in the open position for en-

abling filling of the bore X of the drill string S through the nozzles in the drill bit B.

When drilling operations are commenced, the drilling fluid pressure in the bore X of the drill string S will exceed the pressure in the annulus between the drill string and the walls of the bore hole H and the ball 21 will remain in the open position. When unexpected high pressure formations are encountered the formation pressure will be sensed by the operator sleeve 131 by communication through the flow port 14 into the expansible chamber 39 for urging the operator sleeve to the upper position and closing the bore X of the drill string S with the ball 21. The operator sleeve 22 continually compares the pressure urgings in the chamber 39 and the chamber 35 for closing the ball 21 when the pressure in the annulus exceeds the pressure in the bore X of the drill string S above the ball 21 by the predetermined value.

When it is desired to rotate open the ball 21, pressure in the flow passage 13 above the ball 21 is increased until it approaches within the predetermined value of the well pressure present in the expansible chambers 39 and 45 as the well pressure is communicated through the nozzles into the drill bit B into the flow passage 13 of the well tool T below the ball 21. When the pressure above the ball 21 is increased sufficiently, the operator sleeve will sense the increased pressure and compare it with the well pressure to enable the spring 47 to move the operator sleeve 31 down for rotating the ball 21 back to the open position. At this time the greater pressure in the bore 13 will be below the ball and will equalize with the pressure above the ball 21 by communication through the opening 22 as the ball 21 rotates open. This equalization will result in a pressure increase in the bore of the well conduit above the ball for holding the ball 21 in the open position and which may also be sensed or measured ground level G. The nozzles N of the drill bit B serve to throttle flow into the bore X of the drill string for providing a sufficient pressure differential between the bore X of the drill string S and the well annulus to close the ball 21 whenever pressure decreases in the bore X of the drill string S. As long as the pressure in the bore X in the drill string S is maintained within the predetermined range for holding the valve open, the ball 21 will remain in the open position and the flow, choked by the nozzles N, into the bore X of the drill string S may be bled off at the ground level G through the valve designated at 160. Thus, an inside blowout preventer drilling tool is provided which enables a small pressure differential flow rate upwardly through the bore of the drill string under controlled conditions, but which will shut in the drill string when the upwardly flow rate pressure differential exceeds the predetermined value or control is lost.

In the use and operation of the second embodiment of the present invention, the tubular assembly 100 is assembled in a manner readily apparent from the drawings and mounted with the drill string S by insertion into the flow passage 101 of the sub 102. When the sub 102 is connected in the drill strings with threads 104 and the string S engages sleeve 116, the tubular assembly 100 is moved to engage the annular shoulder 105 of the sub 102 for securing therein. Pressure in the bore X of the drill string S above the ball 121 is then increased for urging on the diaphragm 150 to flex to increase the pressure in the upper expansible chamber 143 to rotate the ball 121 open. With the ball 121 ro-

tated open (FIG. 1), the operator sleeve 131 is in the lower position and the lugs 161 engage the tapered shoulder 114f for latching the operator unit in the lower position. As additional drill string S is added above the well tool T and the tool T lowered into the bore hole H, the lugs 161 and resilient fingers 160 are sufficient to hold the ball 121 in the open position to enable equalization of the levels of drilling fluid in the bore X of the drill string S and in the borehole H to delay closing rotation of the ball 121 and enable filling of the bore X of the drill string S through the nozzles N of the bit B.

During normal drilling operations, pressure of the drilling fluid in the bore X is greater than the pressure exteriorly of the well tool T and the ball 121 is held in the open position. When the pressure in the borehole H exteriorly of the tool T exceeds the pressure in the bore X of the drill string S, the greater pressure will be sensed by the surface 135b and compared with the pressure urging on the surface 134b for urging the operator unit to move upwardly for closing the ball 121. The greater pressure in the chamber 140 required for effecting closure of the ball 121 may be predetermined or controlled by the ratio of the effective surface area 135b to that of the surface 134b. In addition, the adjustment ring 162 will influence or assist in predetermining the pressure differential needed for closing the valve.

With the valve in the closed position, the pressure in the bore X of the drill string S below the ball 121 will equalize with the pressure in the bore hole H effecting closure by communication below the ball 121 will be communicated along threaded engagement 136 for effectively urging upwardly on the operator unit between the seals 141 and 142 and thus the opening and closing pressure responsive surface effecting seals will be identical. However, the opening pressure responsive surface 134b is also sealed by the secondary seals 112 and 144 which in effect reduce the effective surface area of the pressure responsive surface 134b. As a result, the pressure in the bore X above the ball 121 must be increased to a value greater than or vary from the pressure in the bore X below the closed ball 121 to effect opening rotation thereof. Once the ball 121 is rotated open and the pressure equalized in the bore X of the drill string S, the well pressure may be bled off through the valve indicated at 160. The pressure must be bled off at a rate approximating the flow into the bore X of the drill string S through the nozzles N to prevent a sufficient pressure differential to rotate the ball 121 closed. After bleeding the pressure for a sufficient amount of time, the valve 160 may be shut in with the ball 121 remaining in the open position.

As both embodiments of the present invention may be held in the open position by controlling the pressure in the bore X of the drill string S to be substantially equal to the well pressure, well conditions existing below the tool T may be determined. The detail sequence for opening the tool T of each embodiment has previously been set forth herein. In essence, this procedure entails increasing the pressure in the bore X of the drill string S above the tool T to a sufficient value for effecting opening of the tool T and thereafter manipulating the valve indicated 160 to maintain the tool T in the open position. With either of the tools operated open and pressure equalized in the bore X, various well conditions may be determined. Samples of the drilling fluid from the drill bit B location may be determined by

bleeding a sufficient quantity of drilling fluid from the drill string S. Also, with the valve indicated at 160 shut in, the static well pressure may be read or measured by a pressure guage device, indicated at 161. The measured well pressure, when compensated by the hydrostatic pressure of the column of drilling fluid in the bore X, will enable the operator to determine the well pressure at the level of the formation F or the tool T.

With the well pressure at the formation known to the driller, the required or necessary density of the drilling fluid to provide a sufficient hydrostatic pressure head at the formation F to bring the well under control may be easily calculated or determined. This avoids the expense of using too heavy a drilling fluid or wasted circulation time in bringing the well under control. The desired density of drilling fluid may then be made up in the reservoir W and circulated down the bore X of the drill string S through the drill bit B and back to the surface exteriorly of the drill string S to bring the well back under control and enable resumption of drilling operations.

The foregoing disclosure and description of the invention are illustrative and explanatory thereof, and various changes in the size, shape, and materials as well as in the details of the illustrated construction may be made without departing from the spirit of the invention.

I claim:

1. A method of operating a well tool for controlling undesired flow in a well conduit, including the steps of: mounting the well tool with the well conduit to control flow through the well conduit; sensing the fluid pressure exteriorly of the well conduit adjacent the well tool; comparing the sensed pressure exteriorly of the well conduit with the fluid pressure in the well conduit; and opening the well tool to enable flow in either direction through the well conduit when the pressure in the well conduit approaches within a predetermined amount of the sensed pressure exteriorly of the well conduit wherein the well tool is opened to enable the flow when the pressure in the well conduit is less than the pressure exteriorly of the well tool by the predetermined amount.
2. The method as set forth in claim 1, including the step of: closing the well tool to block flow through the well conduit when the sensed pressure exceeds the pressure in the well conduit by the predetermined amount of pressure.
3. The method as set forth in claim 1, including the step of: latching the well tool open to delay operation sufficiently to prevent momentary pressure fluctuations from operating the well tool.
4. The method as set forth in claim 3, including the step of: releasing the latch when the sensed pressure exceeds the pressure in the well conduit by the predetermined amount of pressure for closing the well tool.
5. The method as set forth in claim 1, wherein the step of mounting includes the step of: locating the well tool in the flow passage of the well conduit to enable desired changing of the well tool by disconnecting the well conduit at one location.

6. The method as set forth in claim 1, wherein the step of mounting includes the step of:
arranging the well tool to provide a substantially full opening flow passage through the well conduit when the well tool is opened.
7. The method as set forth in claim 1, including the steps of:
a. controlling the pressure in the well conduit to open the well tool; and
b. determining the value of the sensed pressure through the open well tool.
8. A method of determining well conditions at a location adjacent a ported drill bit and below a closed blowout preventer mounted in a well conduit at a subsurface location in the well, including the steps of:
controlling the fluid pressure in the well conduit above the closed blowout preventer to effect opening of the blowout preventer and for holding the blowout preventer open with controlled fluid pressure for communicating well conditions through the blowout preventer and the ports of the drill bit; and
determining well conditions at a location below the open blowout preventer by flowing a sufficient quantity of well fluids through the blowout preventer and the well conduit to the surface.
9. The method as set forth in claim 8, wherein the step of controlling the fluid pressure in the well conduit includes the steps of:
a. increasing the pressure in the well conduit above the blowout preventer to approach the value of the pressure in the well conduit below the blowout preventer;
b. opening the blowout preventer for equalizing the pressure in the well conduit above the blowout preventer with the pressure in the well conduit below the blowout preventer.
10. The method as set forth in claim 9, wherein the step of determining well conditions includes the steps of:
measuring the equalized pressure in the well conduit above the blowout preventer; and
compensating for the pressure head of well fluids to determine the well pressure.
11. The method as set forth in claim 8, wherein the step of determining well conditions includes the step of:
measuring the well conditions in the well conduit above the blowout preventer.
12. The method as set forth in claim 11, including the step of:
compensating the measured well condition to determine the true well condition.
13. An inside blowout preventer well tool, including:
a frame adapted for mounting with a well conduit at a desired location;
closure means mounted with said frame for movement to and from an open position enabling flow through the well conduit and a closed position blocking flow through the well conduit; and
operator means operably connected with said closure means for moving said closure means to and from the open and closed positions, said operator means moving said closure means to the open position when the pressure in the well conduit exceeds a pressure level predetermined below well fluid pressure externally of the well conduit and adjacent said frame.

14. The apparatus as set forth in claim 13, wherein said operator means includes:
piston means having a first pressure responsive surface for effecting movement of said closure means to the open position in response to pressure in the well conduit effecting urging on said first pressure responsive surface.
15. The apparatus as set forth in claim 14, wherein said piston means further includes:
a second pressure responsive surface for effecting movement of said closure means to the closed position in response to the pressure exteriorly of the well conduit and adjacent said frame.
16. The apparatus as set forth in claim 14, wherein:
said operator means is formed for predetermining the amount of pressure to which the pressure in the well conduit must vary from the pressure exteriorly of the well conduit for opening the closure means.
17. The apparatus as set forth in claim 14, including:
an expandable chamber formed by said frame and said operator means with said first pressure responsive surface exposed to the pressure in said expandable chamber; and
a pressure transmitting fluid disposed in said expandable chamber adjacent said first annular pressure responsive surface for transmitting the pressure in the well conduit to said first pressure responsive surface for effecting movement of said closure means while displacing the well fluids from contact with said first pressure responsive surface to protect said first pressure responsive surface from the well fluids in the well conduit.
18. An inside blowout preventer well tool, including:
a frame adapted for mounting with a well conduit at a desired location;
closure means mounted with said frame for movement to and from an open position enabling flow through the well conduit and a closed position blocking flow through the well conduit; and
operator means operably connected with said closure means for moving said closure means to and from the open and closed positions, said operator means moving said closure means to the open position when the pressure in the well conduit is substantially equal to the pressure externally of the well conduit and adjacent said frame;
said operator means including:
piston means having a first pressure responsive surface for effecting movement of said closure means to the open position in response to pressure in the well conduit effecting urging on said first pressure responsive surface;
- an expandable chamber formed by said frame and said operator means with said first pressure responsive surface exposed to the pressure in said expandable chamber;
- a pressure transmitting fluid in said expandable chamber for transmitting the pressure in the well conduit to said first pressure responsive surface for effecting movement of said closure means while protecting said first pressure responsive surface from the well fluids in the well conduit;
- a movable sealing member enclosing said expandable chamber and having first and second pressure responsive surfaces;
- said first pressure responsive surface of said sealing member exposed to pressure in the well conduit;

said second pressure responsive surface of said sealing member exposed to the pressure transmitting fluid in said expandible chamber, said sealing member moving to transmit the pressure in the well conduit urging on said first surface to the pressure transmitting fluid in said expandible chamber by the urging of said second surface on said fluid pressure transmitting fluid wherein fluid pressure in the well conduit is transmitted into said expandible chamber.

19. The apparatus as set forth in claim 18, wherein: said sealing member is a flexing diaphragm.

20. The apparatus as set forth in claim 19, wherein: said diaphragm is in the form of a tube flexing radially to transmit the pressure into said expandible chamber.

21. The apparatus as set forth in claim 13, wherein: said frame includes a tubular member adapted for connection with a well conduit at upper and lower ends of said tubular member to form a portion of the well conduit.

22. The apparatus as set forth in claim 13, wherein: said frame includes a tubular assembly dimensioned to be introduced in an enlarged portion of a flow passage of the well conduit at desired location for controlling the flow through the flow passage, said tubular assembly operably secured at the enlarged portion of the flow passage of the well conduit after introduction by connection of an adjacent section of well conduit with the portion of the well conduit forming the enlarged portion of the flow passage.

23. The apparatus as set forth in claim 22, wherein: said tubular assembly having an opening therethrough for enabling communication of the flow passage of the well conduit through said tubular assembly, said opening having a cross-sectional flow area substantially equal to the cross-sectional flow area of the flow passage of the well conduit wherein a full opening well tool is provided.

24. The apparatus as set forth in claim 22, wherein: a. said tubular assembly having an opening therethrough for enabling communication of the flow passage of the well conduit through said tubular assembly; and

b. seal means carried by said tubular assembly for effecting a seal between said tubular assembly and the well conduit for directing the flow of fluid through the well conduit to flow through said opening through said tubular assembly.

25. The apparatus as set forth in claim 24, wherein: said seal means carried by said tubular assembly for enabling fluid pressure introduced between said tubular assembly and the well conduit to withdraw said tubular assembly from the flow passage when the well conduit is disconnected.

26. The apparatus as set forth in claim 13, wherein said closure means, includes:

a substantially ball-shaped member having a flow passage formed therethrough, said ball shaped member rotating to and from the open and closed positions for positioning said flow passage for controlling flow through the well conduit.

27. The apparatus as set forth in claim 26, wherein: said flow passage through said ball shaped member having a cross-sectional flow area substantially equal to the cross-sectional flow area of the flow

passage of the well conduit wherein a full opening well tool is provided.

28. The apparatus as set forth in claim 13, wherein said operator means includes:

5 an operator member mounted with said frame for movement to and from a first position for moving said closure means to the open position and a second position for moving said closure means to the closed position.

10 29. The apparatus as set forth in claim 28, wherein: said operator member forms a piston means having a first pressure responsive surface for effecting movement of said operator member to move said closure means to the open position in response to pressure in the well conduit effecting urging on said first pressure responsive surface.

15 30. The apparatus as set forth in claim 29, wherein said piston means further includes:

20 a second pressure responsive surface for effecting movement of said operator member to move said closure means to the closed position in response to the pressure exteriorly of the well conduit adjacent said frame.

25 31. The apparatus as set forth in claim 28, wherein:

a. said operator member includes a sleeve portion, said sleeve portion having a first annular surface and a second annular surface facing in opposite directions;

30 b. said first annular surface exposed to pressure in the well conduit for urging movement of said operator member to the first position for opening said closure means in response to the pressure in the well conduit urging on said first annular surface; and

35 c. said second annular surface exposed to pressure exteriorly of the well conduit and adjacent said frame for urging movement of said operator member to the second position for closing said closure means in response to the pressure exteriorly of the well conduit and adjacent said frame urging on said second annular surface.

40 32. The apparatus as set forth in claim 31, wherein: predetermining a difference in surface area between said first annular surface and said second annular surface predetermines the amount of pressure difference to move said operator member to operate said closure means.

45 33. The apparatus as set forth in claim 31, including: means mounted with said frame for urging said operator to move to the first position for opening said closure means.

50 34. The apparatus as set forth in claim 31, including: means mounted with said operator member for delaying movement of said operator from the first position to the second position to prevent momentary pressure fluctuations from closing said closure means.

55 35. The apparatus as set forth in claim 34, wherein said means for delaying movement, includes:

a. said frame having a shoulder formed thereon;

b. a resilient deformable arm extending from said operator member;

c. a lug formed on said arm at a location spaced from said operator member, said lug engaging said shoulder when said operator member is in the first position to delay movement of said operator member to the second position.

60 65 36. The apparatus as set forth in claim 31, including:

an expansible chamber formed by said frame and said operator member with said first annular pressure responsive surface exposed to the pressure in said expansible chamber; and

b. a pressure transmitting fluid disposed in said expansible chamber adjacent said first annular pressure responsive surface for transmitting the pressure in the well conduit to said first annular pressure responsive surface for effecting movement of said closure means while displacing the well fluids from contact with said first annular pressure responsive surface to protect said first annular pressure responsive surface from the well fluids in the well conduit.

37. An inside blowout preventer well tool, including:
a frame adapted for mounting with a well conduit at a desired location;
closure means mounted with said frame for movement to and from an open position enabling flow through the well conduit and a closed position blocking flow through the well conduit;
operator means operably connected with said closure means for moving said closure means to and from the open and closed positions, said operator means moving said closure means to the open position when the pressure in the well conduit is substantially equal to the pressure externally of the well conduit and adjacent said frame;
said operator means including an operator member mounted with said frame for movement to and from a first position for moving said closure means to the open position and a second position for moving said closure means to the closed position;
said operator member includes a sleeve portion, said sleeve portion having a first annular surface and a second annular surface facing in opposite directions;
said first annular surface exposed to pressure in the well conduit for urging movement of said operator member to the first position for opening said closure means in response to the pressure in the well conduit urging on said first annular surface;
said second annular surface exposed to pressure exteriorly of the well conduit and adjacent said frame for urging movement of said operator member to the second position for closing said closure means in response to the pressure exteriorly of the well conduit and adjacent said frame urging on said second annular surface;
an expansible chamber formed by said frame and said operator member with said first annular pressure responsive surface exposed to the pressure in said expansible chamber;
a pressure transmitting fluid in said expansible chamber for transmitting the pressure in the well conduit to said first annular pressure responsive surface for effecting movement of said closure means while protecting said first pressure responsive surface from the well fluids in the well conduit; and

a flexible diaphragm separating said expansible chamber from the pressure in the well conduit, said diaphragm flexing to transmit the pressure in the well conduit to said pressure transmitting fluid in said expansible chamber for urging on said first annular pressure responsive surface.

38. The apparatus as set forth in claim 37, wherein:

said diaphragm is in the form of a radially flexing sleeve transmitting the pressure into said expansible chamber from the well conduit.

39. A method of operating a well tool having a pressure comparer for controlling undesired flow in a well conduit, including the steps of:

mounting the well tool with the well conduit to control flow through the well conduit;
sensing the fluid pressure exteriorly of the well conduit adjacent the well tool;
transmitting with a transmitting fluid the well fluid pressed in the well conduit to a location in the well tool for comparing while holding the well fluid pressure from contact with a comparer;
comparing the sensed pressure exteriorly of the well conduit with the fluid pressure in the well conduit transmitted by the transmitting fluid; and
closing the well tool to block flow through the well conduit when the sensed pressure exceeds the pressure in the well conduit by a predetermined amount.

40. A method of operating a well tool having a pressure comparer for controlling undesired flow in a well conduit, including the steps of:

mounting the well tool with the well conduit to control flow through the well conduit;
sensing the fluid pressure exteriorly of the well conduit adjacent the well tool;
transmitting with a transmitting fluid the fluid pressure in the well conduit to a location in the well tool for comparing while blocking contact of the well fluids with the comparer;
comparing the sensed pressure exteriorly of the well conduit with the fluid pressure in the well conduit; and
opening the well tool to enable flow through the well conduit when the pressure in the well conduit is substantially equal to the sensed pressure.

41. The method as set forth in claim 40, including the step of:

locating the well tool in the flow passage of the well conduit to enable desired changing of the well tool by disconnecting the well conduit at one location.

42. The method as set forth in claim 39, wherein the step of mounting includes the step of:

arranging the well tool to provide a substantially full opening flow passage through the well conduit when the well tool is opened.

43. The method as set forth in claim 40, wherein the step of mounting includes the step of:

arranging the well tool to provide a substantially full opening flow passage through the well conduit when the well tool is opened.

44. The method as set forth in claim 39, including the steps of:

controlling the pressure in the well conduit to open the well tool; and
determining the value of the sensed pressure through the open well tool.

45. The method as set forth in claim 40, including the steps of:

controlling the pressure in the well conduit to open the well tool; and
determining the value of the sensed pressure through the open well tool.
